UNITED STATES PATENT OFFICE.

WILLIAM E. VARNEY, OF DAYTONVILLE, IOWA.

FLY-NET PUNCH.

SPECIFICATION forming part of Letters Patent No. 247,971, dated October 4, 1881.

Application filed May 25, 1881. (No model.)

To all whom it may concern:

Be it known that I, WILLIAM E. VARNEY, of Daytonville, in the county of Washington and State of Iowa, have invented an Improved 5 Fly-Net-Bar Punch, of which the following is a specification.

The object of this invention is to provide a machine for punching holes for the net-strands in the leather bars or straps more rapidly and 10 accurately than is now done and without removing any of the leather.

Figure 1 is a partly-sectional front elevation of the device on line $x-x$, Fig. 2. Fig. 2 is a 15 sectional end elevation on line $y-y$, Fig. 1. Fig. 3 is a sectional elevation of a portion of the device on line $z-z$, Fig. 1.

Similar letters of reference indicate corresponding parts.

In the drawings, A represents the base or 20 table of the machine, supporting a double standard, A', in which is journaled the horizontal crank-shaft B, through which power is applied to operate the machine. On this shaft B is rigidly secured a spur-wheel, B', which 25 meshes with a corresponding spur-wheel, C', on the shaft C, which latter is journaled in the standard A', parallel with and above the shaft B, as shown. On one end of this shaft C is fixed an eccentric, D, whose vertical connecting-rod D' is connected with the top of the fork 30 or punch shaft E', which latter carries on its lower end the two-pronged fork or punch E.

A guide-frame, F, attached to the standard A' serves to support or hold in a vertical position the fork or punch shaft E', that passes 35 through it. A presser-foot, G, also has its shank G' held in the guide-frame F, parallel with the punch-shaft E', and, within said frame F, is encircled by a spiral spring, G², to keep 40 said foot G pressed down on its work. Said presser-foot G may be raised at any time by turning a handled eccentric, H, that is pivoted on the frame F against a stud, a, that projects from the said presser-foot shank G'.

45 The strap or bar I that is to be operated upon is placed on the table A, between the parallel guides K, which are secured on said table A by screws or studs b, that are passed through their slotted ears c, and said guides 50 K are then adjusted to the width of the said strap or bar I by means of a right-and-left screw, L, that passes through the lugs d of the

guides K, which depend below the top of said table A, as shown in Fig. 1. The strap or bar I is extended along beneath the punch E and presser-foot G, and is pressed by the latter upon the feed spur-wheel M, whose periphery extends slightly up through a corresponding opening in said table A. Said feed-wheel M is keyed on one end of a shaft, M', that is 55 journaled in suitable hangers, f, depending from the under side of the table A, and said shaft M' has secured on its opposite end a ratchet-wheel, O, that is inclosed in a flanged wheel, P, which is loosely secured on the extreme outer end of said shaft M'. Within this wheel P is pivoted a pawl or dog, h, that is designed to engage in the teeth of the ratchet-wheel O intermittently when the machine is in operation, in order to thereby move the feed- 60 wheel M to advance the strap or bar I as required beneath the punch E. This wheel P is connected with the fly-wheel Q on the shaft C by means of an eccentric-rod, P', in such a manner that when the machine is in operation 65 a short rocking motion is given to the wheel P, and thence, by means of the dog h and ratchet O, to the shaft M'. As the strap or bar I is fed along by the feed-wheel M the punch E is moved up and down, and at each downward stroke its points are driven through said strap or bar I, thereby forming, without removing any of the leather, the holes for the netting-strands. The rate of feed of the said strap or bar I may be changed at any time by 70 changing the point of attachment of the eccentric-rod P' with the fly-wheel Q.

With this machine the work of preparing the straps or bars for fly-netting for horses, &c., is performed with great economy of time and 75 labor.

Having thus described my invention, I claim as new and desire to secure by Letters Patent—

In a fly-net-bar punch, the combination, with the punch E, feed-wheel M, shaft M', ratchet-wheel O, dog h, and wheel P, of the shaft C, eccentric and eccentric-rod D D', fly-wheel Q, and eccentric-rod P', substantially as herein shown and described, whereby said punch and feed-wheel are operated, as set forth.

WILLIAM EDWIN VARNEY.
